US00D942724S

(12) **United States Design Patent** (10) Patent No.: **US D942,724 S**
Luburic et al. (45) Date of Patent: ** Feb. 1, 2022

(54) **CONTAINER**(71) Applicant: **BWAY Corporation**, Atlanta, GA (US)(72) Inventors: **Frano Luburic**, Costa Mesa, CA (US);
John Richard Homann, Naperville, IL (US)(73) Assignee: **BWAY CORPORATION**, Atlanta, GA (US)(***) Term: **15 Years**(21) Appl. No.: **29/725,732**(22) Filed: **Feb. 26, 2020**(51) LOC (13) Cl. **07-05**

(52) U.S. Cl.

CLAIM

The ornamental design for the container, as shown and described.

DESCRIPTION

FIG. 1 is a perspective view of an exemplary container;
FIG. 2 is a top view of an exemplary container;
FIG. 3 is a bottom view of an exemplary container;
FIG. 4 is a front view of an exemplary container;
FIG. 5 is a side view of an exemplary container; and,
FIG. 6 is a cross-sectional view of an exemplary container.
The broken lines shown in the drawings illustrate portions of the container that form no part of the claimed design.
